UNITED STATES PATENT OFFICE.

AARON FREEDMAN, OF PHILADELPHIA, PENNSYLVANIA, ASSIGNOR TO THE FIRM OF
W. FREEDMAN AND SONS, OF PHILADELPHIA, PENNSYLVANIA.

LADY'S SKIRT.

1,033,066.

Specification of Letters Patent. Patented July 16, 1912.

Application filed September 22, 1910. Serial No. 583,296.

To all whom it may concern:

Be it known that I, AARON FREEDMAN, a citizen of the United States, residing in Philadelphia, in the county of Philadelphia 5 and State of Pennsylvania, have invented certain new and useful Improvements in Ladies' Skirts, of which the following is a specification.

This invention relates to ladies' skirts and 10 has more particular relation to that class of garments in which the upper portion or waist line may be adjusted to various sizes.

The principal object of the present invention is to provide a garment of the class recited 15 in which the upper portion or waist line may be adjusted to a desired size, by means of inter-locking mediums.

A further object of the present invention is to provide a garment of the class recited 20 in which the upper portion or waist band is formed for the reception of a drawstring, the ends of which are constructed to inter-lock with the waist band of the garment at a point adjacent the vent of the garment.

25 A still further object of the present invention is to provide a garment the upper portion of which is equipped with darts or gussets of pliable material, the said upper portion of the garment including the darts 30 or gussets being formed for the reception of a drawstring, whereby the waist line may be adjusted to desired sizes inter-locking means being present between the drawstring and the garment adjacent the vent thereof 35 for maintaining the waist size thus secured.

A still further object of the present invention is to provide a lady's skirt of neat and attractive appearance, the upper portion or waist line of which may be made adjustable 40 by simple, efficient and comparatively inexpensive means and which shall be comfortable to the wearer.

Other objects of the invention relate to general details of construction and arrangement of parts as will hereinafter appear.

The invention consists of the improvements hereinafter described and finally claimed.

The nature, characteristic feature and 50 scope of the invention will be more fully understood from the following description taken in connection with the accompanying drawings forming part hereof and in which:

Figure 1, is a perspective view of a garment embodying the invention, Fig. 2, is a

fragmentary view of the rear portion of a garment looking from the inside and illustrating the drawstring in unlocked position, Fig. 3, is a top or plan view of Fig. 2, illustrating the drawstring inter-locking 60 with the garment, Fig. 4, is a fragmentary view principally in section and drawn to an enlarged scale of one of the inter-locking mediums disclosed in the foregoing figures, and Fig. 5, is a perspective view of the upper portion of a lady's skirt illustrating a somewhat modified form of gusset.

In the drawings the upper portion or waist line of the skirt 1, and preferably in the rear half of the circumference thereof 70 and upon each side of the waist line are inserted darts or gussets 2, of pliable material. These gussets are formed of material considerably more pliable than the skirt material. In practice the gussets are usually 75 formed of stockinette or similar very pliable material and the skirts are usually formed of silk or other relatively stiff material. The entire circumference of the waist line of the garment 1, including the darts 2, is 80 turned over and attached to the skirt interior as by stitches 3, to form a drawstring receiving space 4. Upon each side of and adjacent the vent 5, of the skirt interiorly considered, the waist band or hem thus 85 formed is apertured as at 6, in button-hole-like fashion through which the respective ends of the drawstring 7, shown as being tape are passed, see Fig. 2. It will be thus understood that the remaining portion of 90 the drawstring 7, encircles the remainder of the upper portion of the skirt, the same being incased throughout by the hem just described. The ends 8, of the tape 7, which 95 are extended through the openings 6, may be equipped upon their outer faces with devices 9, adapted to inter-lock with other devices 10, and 11, united to the inner face of the waist band of the garment. As clearly shown in Figs. 2, and 3, these devices 10—11 100 are located upon each side of and adjacent the vent 5. As clearly illustrated in Fig. 4, the inter-locking devices 9, and 10, constitute a male and female member, and when inter-locking provide a substantially flat attachment thereby provided for the comfort 105 of the wearer of the skirt.

By referring to Figs. 2, and 3, it will be observed that the devices 10, of the waist band are shown as being more widely sep- 110

arated or spaced than are the devices 11. This arrangement and construction of parts is utilized, in order that fine adjustments of the waist band may be secured when the devices 9, of the tape 7, and said devices 10, and 11, are interlocked. Thus, if the hips of the wearer of the skirt are not uniform, such inequality may be taken care of more accurately and more readily by the above 10 arrangement of parts. Obviously, the said devices 10, and 11, may be equally spaced apart if desired. It will be readily apparent that by taking the ends 8, of the tape or drawstring 7, and pulling them 15 toward one another, the puckered waist line may be decreased by virtue of the fact that the gussets 2, being more pliable than the skirt material, take up the fullness of the skirt without, however, leaving the waist line in a bulged or bulky condition. When 20 the desired size has been obtained, such size may be made temporarily secure by uniting the ends of the tape 7, with respect to the waist band of the skirt by virtue of the 25 inter-locking devices 9, 10—11. It may be here stated that if the waist line of the underskirt was in a bulged or bulky condition the outer skirt would not hang evenly and would present a bad appearance. Like- 30 wise if the locking attachments and draw- strings were upon the underskirt exterior they would serve to render an uneven sur- face, thus tending to present protuberances upon the underskirt exterior, which is dis- 35 advantageous.

In Fig. 5, the gusset 12, is shown as being substantially U-shape, in order that addi-

tional fullness of the skirt may be com- 40 pensated for, the drawstring and interlocking attachments being of the construction here- 45 inbefore described.

What I claim is:

A garment of the class described having its waist line fitted with oppositely disposed pliant non-elastic gussets possessing consider- 45 ably more pliability than the skirt material at least a portion of the waist line in- 50 cluding said gussets being of tubular and puckered formation for drawstring accom- 55 modation, said waist line being slotted upon its inner sides adjacent the vent of the garment, drawstring portions for the tubular parts the free ends of which pass through said slots to the skirt interior, a series of 60 fastening devices secured to the free ends of said drawstring portions upon the outer faces thereof, and a series of other fastening devices secured to the inner sides of the 65 waist line upon opposite sides of the vent of the garment, said fastening devices being of male and female construction for inter-lock- 70 ing one with another whereby fullness of the skirt waist line may be compensated for by the pliable vents to provide an even and non-bulky waist line surface when said 75 parts are interlocked, said drawstring por- tions being entirely hidden by the outer skirt parts.

In testimony whereof I have hereunto signed my name.

AARON FREEDMAN.
